UNITED STATES PATENT OFFICE.

HERMANN LEMP, OF LYNN, MASSACHUSETTS, ASSIGNOR TO GENERAL ELECTRIC COMPANY,
A CORPORATION OF NEW YORK.

MEANS FOR REGULATING THE SUPPLY OF FUEL TO BURNERS.

No. 888,243.

Specification of Letters Patent.

Patented May 19, 1908.

Application filed July 27, 1901. Serial No. 69,903.

To all whom it may concern:

Be it known that I, HERMANN LEMP, a citizen of the United States, residing at Lynn, in the county of Essex and State of Massachusetts, have invented certain new and useful Improvements in Means for Regulating the Supply of Fuel to Burners, of which the following is a specification.

When a flash boiler is heated by liquid fuel supplied by a pump operated by the engines, some means is necessary for maintaining a pilot light when the engine stops: usually a small hand pump to force air into the fuel tank and thus create sufficient pressure to feed the fuel to the burner. Instead of a fuel feed pump, the hand pump may be used to maintain an air-pressure approximately fifty pounds per square inch in the fuel tank, the flow of fuel being controlled automatically by the boiler pressure. There are certain practical objections to these systems of fuel supply and the object of my invention is to provide a system which is automatic in its action and is free from all objections.

25 In the accompanying drawing I have illustrated diagrammatically an embodiment of my invention.

Referring to the drawing by reference numerals, 1 represents the main fuel tank which is always in free communication with the air, and is so situated that fuel will flow therefrom by gravity to the burner. The burner is not ordinarily supplied with fuel under gravity feed, but sufficient fuel will flow thereto to assist in starting. By reason of the main tank being subjected to atmospheric pressure only I can add fuel to the supply at any time without in any way changing the condition of the fire, and danger from fire caused by leaks is reduced to a minimum. Situated at some convenient place and preferably at a somewhat lower point than the fuel tank, is an energy-storing device taking, in the present illustration, the form of an auxiliary tank or chamber 2, of small capacity containing air under pressure, and having a small opening connecting it with the fuel pipe. This chamber is designed to feed fuel to the burner when the automatic pump is idle, such for example, as would be the case when the vehicle is standing still with the fire banked. The chamber also assists

in furnishing fuel to the burner when for any reason the pump strokes are very slow. The chamber is provided with a valve 3 and a cap like an ordinary bicycle tire so that an initial pressure may be given thereto—I may use if desired a chamber having a permanent air pressure therein.

The burner consists of a vaporizer 3, a nozzle 4, and a baffling plate 5. In order to clean the nozzle of the burner, a needle 6, is provided which is actuated by the lever 7. Between the auxiliary fuel tank 2, and the burner is a fuel carrying connection 8, which connection includes the adjustable regulating valve 9. The connection 8 shunts or bypasses the pump 10 and regulator so that fuel can be supplied to the burner independently thereof.

The air pressure in the auxiliary tank may be anything that is desired: from thirty to fifty pounds will be found to be satisfactory. The pressure in the pipe 8 will be the same as that of the tank, while the pressure in the pipe between the valve 9 and the burner may be reduced to any suitable amount, preferably from three to five pounds. In other words, the valve is opened just enough to permit sufficient fuel to flow through it to keep the fire in a banked condition; and, by making the auxiliary tank of the proper capacity, this low fire can be maintained for a considerable time: for example, an hour.

An automatic pump 10 is provided which is driven from the engine 11 by means of a belt or chain 12 and the crank disk 13. The pump is of the ordinary single acting type, and is controlled by the valves 14 and 15, which permit fluid to flow in the direction of the arrows but not in the reverse direction. Between the fuel tank 1 and the pump is a connection 16, containing a small regulating valve 17. This valve is set to give a definite opening and performs no part in the ordinary regulation, but is closed when it is desired to leave the vehicle for any considerable length of time. Extending between the pump and the burner is a connection 18, which contains a check valve 19, permitting the fuel to flow in the direction of the arrows but not in the reverse direction, and a regulating valve 20. The latter is set to give the required opening and performs no part in the ordinary regula-

tion, but is closed when it is desired to absolutely cut off the supply of fuel to the burner. The check valve 19 is intended to prevent fuel from being forced back toward the pump 5 when it is idle, and the burner pressure is being supplied from the air containing tank 2. Between the pump and the tank 2 is a connection 21 which contains a check valve 22, that permits fuel to flow in the direction 10 of the arrow but not in the reverse direction.

The automatic pump is designed to deliver fuel in excess. To regulate the delivery of fuel to the burner an automatic regulator is provided containing a valve or disk 23, 15 which is pressed against the seat 24, to a greater or less extent by the steam pressure on the engine 11. When the load is heavy, so that the pressure on the engine side of the throttle is high the valve is firmly seated, 20 and all of the fuel from the pump is forced into the burner, but as soon as the pressure is decreased to a certain point, the valve moves away from its seat and a certain amount of fuel will flow through the by-pass 25 connection 26, to the suction valve 14, of the pump. In other words, a local circuit will be created around the pump. The regulation in the present instance is dependent upon the pressure of the steam on the engine 30 as distinguished from those systems depending upon boiler pressure. By this arrangement any change in the steam pressure on the engine, due to change of load, is immediately detected and compensated for by the 35 automatically acting fuel supply system.

The boiler 25 is designed to furnish superheated steam, and consists of a number of turns or convolutions of small pipe. The particular form of boiler, however, is immaterial as a water tube or shell boiler could be 40 used equally well. The boiler supplies steam to the engine 11 by means of the pipe 27, which contains the throttle valve 28.

The operation of my invention is as follows: Assuming that it is desired to start the 45 system into operation for the first time or after a protracted stop, the valves 17 and 20 are opened which permits fuel to flow by gravity from the tank 1, through the regulator and the check valve 19, to the burner. With the proper starting device this is sufficient to get the burner into operative condition and water can be supplied to the 50 boiler by any suitable pump. As soon as steam is formed and is admitted to the engine the latter starts and with it the automatic fuel pump 10, which pump delivers fuel to the burner by the connection 18 and check valve 19. It also forces a certain 55 amount of fuel up through the check valve 22, to the connection 21, and through the restricted neck of the air containing chamber 2; this compresses the air in the chamber to a greater or less degree, the valve 19 being

so adjusted that there will be sufficient back 65 pressure to overcome the air pressure in the chamber up to a certain point. This pressure can be increased to any desired amount by means of a hand pump connected with the valve 2'. 70

Assuming that the vehicle or other apparatus equipped with my improved fuel supply system is brought to a standstill: This means that in order to operate the system economically the supply of fuel must be cut down, and 75 accordingly the pump is shut down. It is necessary, however, to keep the parts hot in order to have steam for starting and also to avoid the smoke and odor incident to starting, and to accomplish this the auxiliary 80 tank 2 is brought into service. The pressure, due to the air in the tank, may be anything that is desired, and it can be regulated by changing the adjustments of the various valves. Fuel is now forced from the tank 2 85 through the pipe 8 and regulating valve 9 into the burner, and the system will continue to operate in this manner for a considerable period of time, depending upon the capacity of the tank 2. It is intended that 90 the capacity of the tank shall be ample to provide for all reasonable stops. In the event of the apparatus being stopped for an unlimited period of time the valve 9 may be closed, which will maintain the pressure in 95 the tank 2. Moreover the valve 17 may also be closed to prevent the gravity feed.

It will be seen that by my invention I dispense with the hand pump ordinarily used, and that the main fuel tank is under pressure. 100 This does away with an extra part and lessens the danger of fire because the loss of fuel due to a small leak is much less where the fuel is under atmospheric pressure, than when subjected to the pressures 105 ordinarily employed.

Instead of subjecting the main burner to the fuel pressure derived from the tank 2, I may employ an auxiliary burner 29, with the vaporizer tube 30, in close proximity to the 110 main burner so that it will always be in operative condition. The auxiliary burner is shown as connected to the pipe 8 by the connection 31, shown in dotted lines.

It will be noted that a single pump is employed to maintain a supply of fuel to the burner under normal running conditions, and also to maintain the air pressure in the auxiliary tank. The pressure on the fuel in the auxiliary tank will be substantially the 115 same as that of the fuel delivered to the burner, but by reason of the reducing valve 9, the pressure on the fuel delivered to the burner will be materially reduced. When the pump stops running the main supply of 120 fuel stops also, but at this point in the operation the auxiliary tank comes into play and supplies the burner with just enough fuel to 125

the pump, and a valve between the pump and the burner for controlling the pressure of the fuel supplied to the latter.

10. In a fuel supply system; the combination of a main fuel tank, a burner, a pump, a plurality of separate supply connections arranged in multiple between and connecting the pump and the burner, an auxiliary tank which is included in one of the said connections and contains fuel under an initial pressure for supplying the burner when the pump is idle, and an automatic regulator which is included in another of the connections and controls the delivery of the pump.

15. 11. In a supply system, the combination of a burner, a main fuel tank holding fuel at substantially atmospheric pressure, a power driven pump connected with the tank and the burner for increasing the pressure of the fuel supplied to the latter, an auxiliary tank containing fuel under pressure, a separate supply connection leading from the auxiliary tank for automatically supplying fuel to the burner when the pump is not operating, a means for connecting the auxiliary tank to a source of air for placing it under an initial pressure, and a valve in said supply connection for reducing the pressure of the fuel supplied by the auxiliary tank to the burner to maintain the flame in banked condition.

12. In combination, a burner, a fuel supply tank, a connection between the tank and the burner, a pump in said connection for delivering fuel to the burner at high pressure, an energy storing device, a connection leading from the delivery side of the pump to the storing device, and a third connection independent of the aforesaid connections which extends from the energy storing device to the burner to feed fuel to the latter.

13. In combination, a burner, a main fuel tank, an auxiliary fuel tank, a pump which is connected to the main tank and maintains the auxiliary tank under pressure, a direct connection between the pump and the burner, and a controllable connection between the auxiliary tank and the burner which shunts or by-passes the pump.

14. In a system of fuel control, the combination of a burner, a main fuel tank, an auxiliary tank, a pump which is connected to both tanks, a connection from the pump to the burner, a valve which prevents the return of fuel to the pump from the auxiliary tank, a separate fuel carrying connection between the auxiliary tank and the burner, and a means in said latter connection for controlling the passage of fuel from the auxiliary tank.

60 15. In combination, a boiler, a burner therefor, a main fuel tank, an auxiliary fuel tank containing fuel under pressure, a pump connected with the main tank and with the burner and delivering fuel under pressure

from the tank to the burner, a connection between the suction and delivery sides of the pump, a regulator in said connection for controlling the effective delivery of the pump, which regulator is acted upon by steam pressure, and a connection between the auxiliary tank and the burner which is in parallel relation to the pump so that the burner can be supplied with fuel from said auxiliary tank when for any reason the pump fails to deliver the proper amount of fuel to the burner.

16. In a fuel system, the combination of a main tank containing fuel under low pressure, an auxiliary tank containing fuel under a higher elastic fluid pressure and receiving its supply of fuel from the main tank, a means whereby the auxiliary tank can be connected with a source of elastic fluid pressure to give it an initial pressure, a power pump and suitable connections therefor for drawing fuel from the main tank and delivering it to the auxiliary tank under pressure, a check valve preventing the flow of fuel from the auxiliary to the main tank, a conduit for conveying fuel from the pump to the burner independently of the auxiliary tank, a separate conduit for conveying fuel from the auxiliary tank to the burner when the pump is idle or substantially so, and a regulator in the fuel circuit which determines the pressure of the fuel supplied to the auxiliary tank.

17. In a system of fuel supply, the combination of a burner, a main low pressure tank, a power pump which receives fuel from the main tank, an auxiliary tank, connections through which the pump delivers to the auxiliary tank and to the burner, means in one connection by which fuel is held in the auxiliary tank under pressure for feeding the burner when the pump is idle and prevented from flowing to the burner through said connection, a device for permitting the auxiliary tank to be placed under air pressure, a by-pass for the pump, and a regulator which controls the by-pass and regulates the amount of fuel delivered to the burner.

18. In a motor vehicle, the combination of a propelling motor, a boiler for supplying motive fluid to the motor, a burner for the boiler, a fuel reservoir, a pump connected with the reservoir and delivering fuel to the burner, means for operating the pump from the motor, a pressure chamber connected with the pump delivery and with the burner for supplying fuel to the latter under certain conditions, a throttling device controlling the supply of fluid to the motor, and means sensitive to the pressure on the motor side of the device for controlling the supply of fuel to the burner independently of the speed of the motor.

19. In a motor vehicle, a propelling motor for said vehicle, a boiler connected with said

maintain it in a banked condition so that it is ready for starting at any instant without thought on the part of the operator other than to admit steam to the engine by throttle
 5 28. In other words, a high and a low pressure fuel service are provided, the high pressure service working when the machine is running and the low pressure when it is standing still, the two being arranged to
 10 coat in such a manner that when one stops or nearly stops the other starts into operation. When the system is in full operation little or no fuel will flow through the valve 9, because the pressure in pipe 18 is so much
 15 greater; but as the pressure decreases in pipe 18, the flow of fuel from valve 9 increases.

In accordance with the provisions of the patent statutes, I have described the principle of operation of my invention, together
 20 with the apparatus which I now consider to represent the best embodiment thereof; but I desire to have it understood that the apparatus shown is only illustrative and that the invention can be carried out by other means.
 25 What I claim as new, and desire to secure by Letters Patent of the United States, is,—

1. In combination, a boiler, a burner, a source of fuel supply, a pump for increasing the pressure of the fuel supplied to the burner, an engine supplied from the boiler and driving said pump, an energy storing device acted upon by the fuel pump which returns its energy to the fuel system when the action of the pump is decreased to a certain
 30 point or stopped, and a steam pressure regulator for controlling the delivery of the pump which is actuated by the steam on the engine side of the throttle.

2. In combination, a boiler, a burner, a source of fuel supply, a pump for increasing the fuel pressure, an engine supplied from the boiler and driving said pump, an auxiliary tank in the fuel circuit which contains air under pressure, a steam pressure regulator
 45 for governing the action of the pump, and a connection extending from the regulator to a point in the steam pipe, between the engine and the throttle, for admitting steam to the regulator.

50 3. In combination, a boiler, a burner for heating the boiler, an engine receiving steam from the boiler, a fuel pump driven by the engine, a supply tank containing fuel at atmospheric pressure, an auxiliary tank containing fuel under pressure above that of the atmosphere, a stop valve between the tanks, a connection between the auxiliary tank and the burner, a valve in said connection, a by-pass around the pump, and a steam actuated
 55 regulator for opening and closing the by-pass.

4. In combination, a boiler, a burner, a main fuel tank, an auxiliary tank, a connection between the auxiliary tank and the burner through which fuel is supplied to main-

tain the burner flame in banked condition, a pump having a separate connection to the main tank and the burner for delivering fuel directly to the latter, a connection between the delivery side of the pump and the auxiliary tank, and means for regulating the flow of fuel to the burner.
 65

5. In combination, a burner, a main fuel tank holding fuel at atmospheric pressure, an auxiliary fuel tank, a connection between the auxiliary tank and the burner for supplying fuel to maintain the flame in banked condition, a pump connected with the main tank, a connection between the pump and the burner which is separate from the first mentioned connection for delivering fuel to the burner under normal pressure, and a connection from the pump to the auxiliary tank for supplying fuel thereto under a pressure above that of the atmosphere.
 75

6. In combination, a boiler, a burner, a main fuel tank, an auxiliary fuel tank containing fuel under a pressure greater than that of the main tank, a pump for maintaining the pressure of the auxiliary tank and also for supplying fuel to the burner from the main tank, a connection from the auxiliary tank to the burner, a check valve to prevent fuel from being forced from the auxiliary into the main tank, a by-pass around the pump, and a steam pressure regulator for controlling said by-pass.
 90

7. In combination, a burner, a fuel pump, a main tank which supplies the pump, an auxiliary tank which receives its supply from the pump, a connection from the pump to the burner, a separate connection from the auxiliary tank to the burner, and means which permits the pump to deliver fuel to the auxiliary tank but prevents fuel in said tank from flowing back to the first mentioned connection or to the main tank.
 100

8. In a fuel supply system, the combination of a main fuel tank, a burner, a connection between the tank and the burner, a pump located in the said connection for supplying fuel to the burner under high pressure, an auxiliary tank whose contents are under an initial air pressure, said tank receiving its supply from the pump, and a connection leading from the auxiliary tank which is independent of the first connection and supplies fuel to the burner at a pressure lower than that due to the pump.
 110

9. In a fuel supply system, the combination of a burner, a high pressure fuel pump which is connected with the burner to deliver fuel directly thereto, an auxiliary tank in which the fuel is maintained under high pressure by the pump, a separate connection between the auxiliary tank and burner by which fuel is supplied to the latter at a pressure different from that of the fuel supplied by the pump, a main fuel tank which supplies
 115
 120
 125

motor, a burner, a fuel reservoir, a pump connected with said reservoir and delivering to said burner, means to operate the pump from said motor, a pressure chamber connected with the pump delivery which is adapted to supply the burner under banked conditions, a means which prevents fuel from flowing from the chamber to the burner through the pump delivery connection, a by-

pass around said pump, and a pressure regulator in said by-pass which regulates the supply of fuel to the burner. 10

In witness whereof, I have hereunto set my hand this 23d day of July, 1901.

HERMANN LEMP.
